J. J. PARKINSON

WATER CLOSET

Filed March 15, 1920

INVENTOR.

John J. Parkinson
BY Munn & Co.

ATTORNEYS

UNITED STATES PATENT OFFICE.

JOHN J. PARKINSON, OF CHICAGO, ILLINOIS.

WATER-CLOSET.

Application filed March 15, 1920. Serial No. 365,907.

To all whom it may concern:

Be it known that I, JOHN J. PARKINSON, a citizen of the United States, and a resident of the city of Chicago, in the county of 5 Cook and State of Illinois, have invented a new and useful Improvement in Water-Closets, of which the following is a full, clear, and exact description.

An object of my invention is to provide 10 a water closet in which the bowl may be flushed without the use of the ordinary valves, which are apt to leak, and which, being made of rubber or similar material, are apt to deteriorate.

15 A further object of my invention is to provide a flushing device in which an air seal takes the place of the ordinary ball valve, but in which there is no actual engagement of moving parts, thus rendering 20 the life of the air seal valve practically indefinite.

A further object of my invention is to provide a device which is relatively simple in construction and which, therefore, is not 25 liable to easily get out of order.

Other objects and advantages will appear 30 in the following specification, and the novel features of the invention will be particularly pointed out in the appended claims.

35 My invention is illustrated in the accompanying drawings, forming part of this invention, in which—

Figure 1 is a front elevation of the device, and Figure 2 is a vertical section 35 through the device.

In carrying out my invention, I provide a bowl 1 of a conventional shape which may be made of any suitable material and which is provided with a discharge pipe 2, having 40 the usual water seal or trap 3. The pipe 2 is preferably covered by the casing 4 which is made integrally with a tank 5 secured above and to the rear of the bowl. The latter is provided with a removable cover 6. 45 In the rear wall of the tank 5 is an inlet pipe 7 which is controlled by means of a float and lever device 8 of ordinary construction.

Secured to the rear wall of the tank is an 50 L-shaped bracket 9, to which is clamped a pipe 10 bearing at its lower end an inverted cup-shaped member 11. A lever 12 is pivoted at 13 on the bracket 9 and bears a valve 14 in the shape of a metal cup having 55 a washer 15 which is arranged to engage

the upper end of the pipe 10 so as to close the latter. The lever 12 has a beveled end 12^x which is arranged to be engaged by the beveled end 16^x of a push rod 16. The latter passes through a bracket 17 and also through the front wall of the tank 5 and is held normally by a spring 18 in a retracted position, that is to say, out of engagement with the end of the lever 12. A float 19 is secured to the lever 12 near the beveled end 60 65 thereof.

Arranged to project through the bottom 20 of the tank 5 is a discharge pipe 21 which has a goose-neck trap or water seal 22; and which communicates with the discharge 70 openings 23 leading into the bowl by means of a passage 24. At the front of the bowl is a large discharge opening 25.

From the foregoing description of the 75 various parts of the device, the operation thereof may be readily understood. The water which is admitted through the intake 7 when the tank is empty fills up on the bottom and rises into the cup-shaped member 11. The water seal 22 has been previously closed and the air is trapped between 80 the water seal and the rising surface of the water as it forces its way upwardly into the member 11. Before the water reaches the top of the discharge pipe 21, there will be 85 balance of pressure, the air being compressed in the pipe 21 and also in the tube or pipe 10. It is obvious that the lever 12, together with the float 19, is heavy enough 90 to keep the cup 14 normally seated. When 95 the tank is full, the intake is shut off in the usual manner by the operation of the float or lever 8.

When it is desired to flush the tank, the 100 push rod 16 is manipulated, and the lever 12 is lifted by the engagement of the end of the push rod with the end of the lever. This raises the valve 14 and permits the air in the pipe 10 and in the cup-shaped member 11 to escape, whereupon the water in the tank will flow out through the discharge pipe 21 and into the bowl, thus flushing the latter. The holes 23 in the bowl are made tapering, and the result is to spread the water out into a sheet. The major portion 105 of the discharge into the bowl, of course, occurs at the large opening, thus insuring the proper flushing of the bowl. When the water has run out, the tank will be refilled in the ordinary manner, and, since the spring 110

18 retracts the push rod, the water will be held in the tank until the rod is again pushed.

In case the valve in the inlet pipe 7 should leak and the water in the tank should rise, it will engage the float 19, thus exerting upward pressure on the lever 12 and releasing the water in the pipe 10. The water in the tank will thereupon run out, and 10 this will be repeated every time the tank is full, thus preventing an overflow, and calling attention to the fact that the inlet is not operating properly.

It will be seen that I have disposed of 15 the usual ball valve which is liable to get out of order and to deteriorate. The water seal forms a perfect check for the water, but permits the instant discharge of the tank when the air is released.

20 I claim.

1. The combination of a bowl and tank 25 for holding water, a discharge pipe having a portion arranged to extend through the bottom of the tank and being provided with a goose-neck water trap, said discharge pipe communicating with said bowl, a bracket secured to the wall of the tank, a pipe carried by the bracket, an inverted cup-shaped member carried by the pipe and arranged to receive the end of said discharge pipe, said 30

cup-shaped member being spaced from the discharge pipe, a lever pivotally mounted on said bracket, a valve carried by the lever and arranged to fit over the end of the pipe to close the latter, and means for operating the lever at will, said last named means comprising a spring pressed push rod having a beveled end arranged to engage the end of the lever to lift the latter.

2. The combination of a bowl and tank 40 for holding water, a discharge pipe having a portion arranged to extend through the bottom of the tank and being provided with a goose-neck water trap, said discharge pipe communicating with said bowl, a bracket secured to the wall of the tank, a pipe carried by the bracket, an inverted cup-shaped member carried by the pipe and arranged to receive the end of said discharge pipe, said 45 cup-shaped member being spaced from the discharge pipe, a lever pivotally mounted on said bracket, a valve carried by the lever and arranged to fit over the end of the pipe to close the latter, means for operating the lever at will, said last named means comprising a spring pressed push rod having a beveled end arranged to engage the end of the lever to lift the latter, and a float secured to said lever near the free end thereof.

JOHN J. PARKINSON.
